UNITED STATES PATENT OFFICE

ERNEST R. SWANSON, OF CRANSTON, RHODE ISLAND, ASSIGNOR TO UNIVERSAL WINDING COMPANY, OF BOSTON, MASSACHUSETTS, A CORPORATION OF MASSACHUSETTS

APPARATUS FOR TWISTING YARN AND THREAD

Application filed March 26, 1929. Serial No. 350,075.

This invention relates to a novel and improved method of producing ply or cabled yarn and thread and consists in improvements in the apparatus for carrying out the process.

The present improvement consists in general in supplying the strands for twisting from cops, cones or other packages wound in multiple with the required number of ends and arranged to deliver over their ends with the packages magazined in series by tying them heel to toe; that is, with the last end from one supply connected to the leading end of a reserve supply, so that the 15 yarns will deliver continuously while new packages are being creelied to replace the exhausted ones.

A particular object of the improvement is to provide for continuous delivery of the 20 ends in multiple to the twister-spindles without requiring the stopping of the twister for doffing the exhausted supplies and replacing them with fresh ones, whereby the productive capacity of the twister is very 25 materially increased.

Another object of the improvement is to avoid the doffing of all of the supplies for the numerous spindles on the twister at one time, as has heretofore been required, which 30 results in leaving considerable yarn on the doffed packages, amounting to a large quantity of waste or dead yarn in the aggregate and representing a capital investment which is a loss to the mill in which the process is 35 practiced.

Another object of the improvement is to provide a twister frame having a creel from which the yarn delivers continuously to the twister-spindles without requiring repeated 40 threading up through the thread-guides and feed-rolls, and on which the supply-packages may be more conveniently and expeditiously creelied while the twisting operation is 45 under way.

Further objects of the improvement are set forth in the following specification which describes a preferred method of carrying out the new process and a preferred form of 50 construction of the machine and apparatus

used therewith as illustrated by the accompanying drawings. In the drawings:

Fig. 1 is a part-sectional end view of a twister-frame provided with a magazine creel for holding the supply packages which 55 deliver the ends continuously to the twister-spindles;

Fig. 2 is a front view of a portion of the twister-frame and creel; and

Fig. 3 is a detailed view showing two of the 60 associated supply-holders of the creel and illustrating the manner of tying up the ends of the packages thereon, and also the method by which the exhausted supplies are doffed 65 and fresh packages creelied in their place. 65

In the present specification the invention is shown and described as applied to use with a ring-twister equipped for wet twisting, but it is to be understood that the improved process may be carried out on twister-frames of other types and styles. In 70 Fig. 1 of the drawings, 2 designates the end-member of the twister-frame and 3 one of the intermediate cross-members or samsons which support the rails of the machine from 75 the floor. The longitudinal side-rails 4 carry bolsters 5 for the twister-spindles 6 which are driven from a central drum or cylinder 7 by means of bands 8 passing around their whirls 9. The present drawings show only 80 the essential parts of the twister without the operating mechanism therefor, 10 designating the ring-rails, 11 the rings carried thereon and 12 the travelers.

Extending horizontally at either side of the 85 frame are longitudinal roll-beams 15, to which are attached the thread-boards 16 carrying the wire thread-guides 17, one for each twister-spindle. The bottom feed-rolls 19 are journaled in bearings on brackets 18 90 mounted on the roll-beams 15, and the top-rolls 20 which co-operate therewith are rotatably held thereabove.

For wet twisting a water or emulsion trough 23 is employed at the rear of each set 95 of feed-rolls with a suitable glass rod or brass roll 24 immersed therein to adapt the strands γ to draw therearound to dampen the yarn. From the trough 23 the strands 100 γ lead forward over and around the top-rolls

20, thence down under the bottom-rolls 19, and passing through the thread-guides 17, draw down to the travelers 12. Above the troughs 23 are traverse-rods 25 carrying a series of thread-guides 26 for guiding the strands down to the wet-rolls 24 while imparting a lateral traverse thereto in the usual manner.

In carrying out the present improved process I may employ any suitable form of creel for holding the supplies to deliver their yarns over the ends of the packages with the latter magazine as previously explained. As a convenient form of construction I may 10 employ a double creel supported from cross-frames or brackets 28 fastened to cross-beams 29 carried on the samsons 3. The oppositely extending arms of the cross-frames 28 are provided with hubs 30 for holding the ends 15 of horizontally extending rods or pipes 31 which constitute the bottom supports for the creel frame. The creel frame may be constructed from piping with upright pipes 32 supported from the lower pipes 31 by means 20 of T-fittings 33 as shown in Fig. 2. The upper ends of the upright pipes 32 are connected to longitudinally extending rods or pipes 34 by means of clamps 35 secured thereto by bolts 36. The uprights or pipes 32 25 form the supports for the supply-holders to be later described.

Spaced along the center of the creel at intervals between the uprights 32 are two series of parallel vertical bars 39 carrying 30 pigtail thread-guides 40. The vertical bars 39 may be constructed of strap metal, having feet 41 bent to overlie a horizontal board or shelf 42 supported on the cross-frames or brackets 28, the feet being fastened to the shelf by bolts 43 or other suitable means. The upper bent ends of the bars or uprights 39 are joined by straps 44 and connected to horizontally-extending pipes 45 by means of 35 U-shaped clamping bolts 46. Extending between the inner and outer horizontal pipes 45 and 34 are suitable frames or struts 47 which act to brace and stiffen the whole structure.

In the present drawings the double creel 40 is illustrated as adapted to support supply packages of conical form, but it is to be understood that parallel packages or supplies of any other form may be used in place of the cones herein shown. In any case, 45 however, the supply packages are supported non-rotatably on spindles or holders which adapt them to deliver the yarn over their ends. In the present improved construction of the creel the supply-holders 50 are arranged to pivot on the uprights 32 to adapt them to swing outwardly at the front of the twister-frame to facilitate the doffing of the empty supplies therefrom and the creeling of new packages thereon.

50 As illustrated most clearly in Fig. 3, each

supply-holder 50 comprises a hub 51 mounted to turn on the upright or pipe 32 and supported in position by a collar 52 secured fast to the pipe, see Fig. 2. Preferably, the hubs 51 have detent-portions 53 which engage 55 suitable notches in the collars 52 to maintain the supply-holders in operative position as illustrated in Fig. 3 of the drawings. Extending angularly from the hubs 51 are curved arms 54 provided at their ends with 57 spindles 55 for insertion into the bores of the wooden tubes 56 which carry the yarn cones or cones C. The spindles 55 may be of any suitable construction as adapted for the particular type of cop-tube or yarn-receiver used as the interior support for the package. As herein shown, the spindles 55 are in the form of skewers having prongs or detent-lugs 57 at their ends which engage with annular grooves or recesses 58 in the bores of 63 the wooden cone-tubes 56.

A preferred form of construction of a twister equipped with the magazine creel having now been described, the method of carrying out the improved process thereon will next be explained in detail. It will be understood that a plurality of yarn-cones or packages are supplied for each twister-spindle, and in the present drawings the double creel is illustrated as being provided with supply-holders arranged in pairs supported in tiers on the uprights 32. With the present type of twister-frame the feed-rolls 19 and 20 are arranged in groups of five along each side of the machine, and the supplies for each group consist of ten yarn-cones C arranged in two rows between each pair of uprights 32. That is to say, each of the end uprights carries five supply-holders 50 and each intermediate upright carries ten supply-holders, half of them projecting from one side and the other half from the opposite side.

Referring to Fig. 3 of the drawings, for convenience in creeling the packages or cones the supply-holders 50 are swung out into the position illustrated by dotted lines in this view and the cones applied to place thereon by sliding the cone-tubes 56 onto the spindles 55 to engage the detent-lugs 57 with the recesses 58 in the tubes. After each package is placed on its supply-holder 50 the latter is swung back into the position illustrated in full lines in Fig. 3 and the detent 53 on its hub 51 will engage with the notch in the collar 52 to hold it in operative position.

When the packages or cones C are wound the first end of the strands, indicated at y' in Fig. 3, is coiled in a groove or depression 60 at the base of the cone-tube 56 to provide a surplus length of yarn for splicing to the leading end of the next cone to be magazine. In creeling the supplies the operator uncoils a sufficient length of yarn y' to tie to the leading end y' of the next adjacent cone C' in 1

the series. After all of the cones have been 5 creeled and magazined by splicing them heel to toe in the manner as above explained, the leading ends y from the first cones C are carried down to the twister-spindles 6 in the following manner. Starting with the upper cone C of the right-hand vertical row as shown in Fig. 2, the strands y are threaded through the guide or pigtail 40 in line with the axis of the cone, see Fig. 1, and thence 10 drawn down to the first guide 26 on the traverse-bar 25. From the guide 26 the strands y are led down under the rod or wet-roll 24, thence over and around the top-roll 15 24, and under the bottom-roll 19 to the guide 17 on the thread-board 16. From this point the strands y are drawn down to the traveler 12 on the ring-rail 10 and fastened to the bobbin b . The strands from the next lower 20 cone C are threaded in the same manner through their respective guide 40, down around the rod 24 and thence to the second pair of rolls which feed them to the next twister-spindle in the series, and so on with 25 each double row of supplies; it being here noted that in the case of the second set of cones C and C' the threading is shown as in reverse order with the strands y delivering first from the left-hand cone instead of 30 from the right-hand one. While this order is a matter of choice, the arrangement shown is preferable as it brings the two vertical rows of reserve cones C' in adjacent relation for convenience in doffing and creeling up. That 35 is to say, the first cones to be exhausted will be located in adjacent rows so that the operator need not move from one position to another in creeling a double row of cones after the ends start to deliver from the connected reserve cones.

It will be understood that with the arrangement as herein shown the supplies are wound in multiple, that is, with the required number of ends on each cone in accordance with 40 the number of ply of the yarn to be produced. For some purposes, in creeling and magazining the supplies the ends are tied together with a bunch knot, but in other instances, to 45 secure a high quality in the product the multiple ends may be separated and tied individually at different points so as to avoid a bunch or enlargement in the finished yarn.

When the twister is started to operate, the 50 multiple strands y from the first set of cones C of the series will be drawn off over the ends of the packages under the action of the feed-rolls and fed to the twister-spindles 6 to be wound onto the bobbins b . Through the provision of the magazine creel having the 55 ends from the supply packages tied heel to toe a continuous delivery may be maintained so that it is not required to stop the twister for doffing the empty supplies and creeling fresh packages. That is to say, the strands 60 for each twister-spindle will deliver first from

the cone C and after the yarn on this cone is exhausted the supply will continue from the reserve cone C' . After the yarn on the first set of cones C is exhausted the doffer passes along the front of the frame and swinging 70 back the supply-holders 50 doffs the empty supplies therefrom and places fresh cones thereon. The leading ends of the strands from these new reserve cones are then tied to the last ends of the strands on the delivering cones, and preferably, the spliced ends are coiled about the heel or base of the cones to take up the slack.

As the twisting operation continues and the yarn is exhausted from the second set 80 of cones C' the last-creeled supplies will commence to deliver so that another set of reserve cones may be creeled, and in this way a supply of yarn is always maintained for each twister-spindle during the continuous 85 operation of the machine.

Heretofore in the present art it has usually been the practice to stop the twisting operation to doff the exhausted supplies and creel and tie up the ends of the new cops or 90 packages. The creeling of a large number of supplies necessarily requires considerable time to accomplish and therefore the twister-frames must be stopped for relatively long periods which occur at frequent intervals. 95 This stopping for doffing and recreeling very materially curtails the productive capacity of the machine. Furthermore, and quite as serious, the previously used practice of stopping the machine for doffing and recreeling 100 results in a loss of yarn. As well known, all of the supply-packages do not contain the same amount of yarn and due to this and other conditions the ends will not run out all at the same time. When the first supply 105 runs out a very considerable amount of yarn may be left on certain other supplies and as all of the packages are doffed at the same time this results in leaving a large amount of yarn on the containers as waste or dead 110 yarn.

In some cases the yarn remaining on the packages is rewound while in other instances the new packages are wound over the dead yarn so that in either case there is a loss. In 115 the case where the dead yarn remains on the packages for repeated handlings it represents a certain capital investment which may be very considerable in the aggregate for a mill operating a large number of spindles. 120 It will therefore be seen that in addition to eliminating the stops for doffing and recreeling with a consequent increase in the productive capacity of the twister, the present invention provides for using up all of the yarn on 125 the cops or packages so that the loss from waste or dead yarn is entirely done away with. For these reasons the present improvement provides important economies in the process of twisting ply or cabled yarn 130

and thread by increasing the productive capacity of the twister, eliminating losses from rewinding or dead yarn, while also reducing the labor costs.

5 In some instances the twisters are run continuously and the individual supplies doffed as they become exhausted, this practice necessitating that the operator be at the proper location as the supply runs out. It is impossible, however, for an operator tending a 10 large number of twister spindles to always reach a supply at the instant that it runs out and therefore it is the common practice to doff a group of supplies before the yarn on 15 all of them is entirely exhausted. As in the former case this practice also results in waste yarn.

With the present improved process the operator is not required to move back and forth 20 from one location to another to reach the supplies as they run out, but is allowed a liberal period of time to creel the reserve supplies in regular order while the last-creeled supplies are running. For this reason the operator can tend more spindles, thus reducing 25 the labor cost.

It is believed that the present improved process is the first to provide for twisting yarns from magazine supplies with the delivery maintained continuous to eliminate 30 stoppages for doffing and recreeling, whereby to attain the advantages and economies herein set forth. Therefore, the invention is herein claimed broadly without limitation as to the 35 apparatus employed in carrying out the process.

While I have herein illustrated a preferred form of the apparatus, including a double magazine creel applied to the twister-frame, 40 it is to be understood that various modifications may be made in the form and construction of the machine and with respect to the method of carrying out the improved process.

Therefore, without limiting myself to the 45 particular form of construction shown or to the precise method described, I claim:

1. An improved twister-frame comprising a plurality of twister-spindles, feed-rolls for feeding the strands to the twister-spindles, and a creel for holding non-rotatable cops, cones or packages to adapt the yarn to deliver over the ends thereof, said creel being provided with a plurality of thread-guides through which the strands draw to direct 55 them to the twister-spindles, a plurality of supply-holders arranged with the axes of two associated holders in a substantially horizontal plane and directed toward a single thread-guide to adapt the packages to be 60 magazine to deliver the yarn first from one package and then from another to maintain a continuous delivery to all of the spindles without arresting the operation of the twister to doff the exhausted supplies and recreel fresh supplies, and means for hinged

mounting the supply-holders to adapt them to turn about vertical axes whereby they may be individually swung outwardly at the front of the frame to facilitate doffing the exhausted packages and replacing them with 70 fresh packages.

2. A twister-frame comprising twister-spindles, means for feeding multiple ends to the twister-spindles to produce a yarn therefrom, a creel comprising a framework, a 75 plurality of thread-guides supported in rows on said framework, and a plurality of supply-holders hingedly mounted to swing about vertical axes at the front of the framework and arranged in pairs with the axes of two 80 associated holders directed toward a single thread-guide, said supply-holders adapted to be individually swung out into position above the twister-spindles to facilitate the doffing of the supplies therefrom and the recreeling 85 of fresh supplies thereon.

3. A twister-frame comprising twister-spindles arranged in rows on the opposite sides of the machine, pairs of feed-rolls arranged above each spindle to adapt them to 90 deliver the multiple strands thereto, and a creel arranged above the frame, said creel provided with a support carrying rows of thread-guides of a number equal to the number of twister-spindles, and supply-holders supported at the front of the creel and arranged in pairs with the axes of two associated holders directed rearwardly toward a single thread-guide to adapt the strands to feed continuously first from one supply and then from another and to be guided toward the center of the frame and thence downwardly to the twister-spindles, said supply-holders being hinged on vertical axes to adapt 95 them to be individually swung outwardly from the front of the creel to facilitate doffing the exhausted supply-packages and recreeling new packages in their place.

4. In a twister, the combination of a frame having opposite rails, twister-spindles rotatably supported on the rails at either side of the machine, ring-rails co-operating with the twister-spindles, feed-rolls arranged at opposite sides of the machine with a pair of rolls for each spindle, a double creel having 110 vertical standards at the center of the frame, thread-guides supported in rows on said standards, uprights on the creel spaced outwardly from the central standards in position above the twister-spindles, and supply-holders hinged on said uprights to adapt them to be individually swung forwardly into position over the twister-spindles, said supply-holders being arranged in pairs and normally held in position with the axes of two 115 associated holders directed toward a single thread-guide on the central upright of the creel.

5. In combination with a twister-frame, 120 standards at the opposite ends of the frame,

rods extending horizontally between said standards on opposite sides of the frame, uprights supported from said rods and arranged in spaced relationship along both sides of the frame, supply-holders pivoted on said uprights to adapt them to swing in horizontal planes and provided with means for supporting yarn-cops, a series of uprights extending in spaced relationship along the center of the frame, thread-guides mounted on said last-named uprights, and detent-means for normally maintaining the supply-holders with the axes of two associated holders alined with a single thread-guide whereby the yarn from the packages carried thereon may be caused to deliver first from one package and then from the other package with a continuous delivery, said detent-means being releasable whereby the supply-holders may be swung outwardly at the front of the frame to facilitate doffing the exhausted yarn-packages and creeling fresh supplies in their place without interrupting the operation of the twister-frame.

In testimony whereof I hereunto affix my signature.

ERNEST R. SWANSON.
